UNITED STATES PATENT OFFICE.

HERMAN GOLDBERG, OF CHICAGO, ILLINOIS, ASSIGNOR TO WOLFE COAL SAVER COMPANY, OF CHICAGO, ILLINOIS, A CORPORATION OF DELAWARE.

DAMPER-GAGE.

1,348,939.

Specification of Letters Patent. Patented Aug. 10, 1920.

Application filed November 24, 1919. Serial No. 340,144.

To all whom it may concern:

Be it known that I, HERMAN GOLDBERG, a citizen of the United States, residing at Chicago, in the county of Cook and State 5 of Illinois, have invented certain new and useful Improvements in Damper-Gages, of which the following is a specification.

My invention relates to gages for draft mechanism and has for one of its objects the 10 provision of a simple and efficient gage means so that an operator may quickly and easily set the damper arrangement of a furnace, and the like, to operate in any desired manner.

15 A further object is the provision of a gage plate for damper mechanism having a plurality of buttons or other damper chain-engaging members which are adjustably mounted in the plate.

20 A still further object is the provision of a simple and efficient gage plate for damper mechanism which can be easily and conveniently secured in convenient position to an operator.

25 Other objects will appear hereinafter.

An embodiment of my invention is indicated in the accompanying drawing, forming a part of this application, and in which—

30 Figure 1 is a front view of a furnace equipped with a device embodying my invention; and

Fig. 2 is an enlarged fragmental section taken on line 2—2 in Fig. 1 of my improved 35 gage.

In the drawing I have indicated a furnace arrangement 5 equipped with a smoke pipe having an enlargement 6 housing a damper with a lever 7 disposed on the outside of said 40 enlargement. My improvement it will be apparent is capable of use with various forms of furnace and draft control mechanism, that shown being simply illustrative.

A check draft damper 8 is hinged at 9 to 45 suitable parts of the smoke pipe. A flexible member 10, which in the present instance is indicated as being a chain, is connected at its lower end to lever 7 and extends upwardly and over a pulley 11. A flexible member or 50 chain is attached to the check draft damper 8 and extends upwardly over a pulley 14 and then horizontally for a distance and attached to a wire or its equivalent and the latter attached to a chain or other flexible member 13 at a point 12. The chain 13 ex-

tends through a pulley 14 and downwardly to a ring 17 for attachment to my improved damper gage. The upper end of chain 10 is attached to the chain secured to damper 8 in any desired manner and may be attached 60 where the last-mentioned chain is secured to the wire above referred to. The length and arrangement of the flexible members, chains or wires, may be varied to suit different requirements.

65 My improved gage comprises a plate or block 18 which is adapted to be secured to a portion of the furnace, as indicated in Fig. 1, or to any other convenient object so as to be easily accessible to the operator. It is 70 very convenient to have the plate attached to the furnace as indicated so that the operator during fixing the fire can set his draft mechanism quickly and easily.

In the form of my invention illustrated 75 I have shown a plurality of slots 19 extending longitudinally of the block or plate 18, and in each slot is disposed the stem 20 of a button or other member 21. I preferably 80 arrange the slots 19 so that they are of various lengths and they may be graduated as indicated in Fig. 1. At the top of the shortest slot may be arranged the notation "Bank." Above the next longer slot the 85 notation "Mild." Above the next slot the notation "Cold" and above the next or longest slot the notation "Ex. cold." I have indicated these notations simply as suggestive. It will be apparent that other notations may be added which will be more 90 convenient under various circumstances. It will also be apparent that a greater or fewer number of slots may be provided with a greater or fewer number of notations near them.

95 I preferably place a button 22 in a fixed position at the top of plate 18 and arrange the draft chains so that the damper is open when the ring 17 is in engagement with the button 22. The buttons 21 in the slots are 100 then arranged along the slots 19 so that when ring 17 is in engagement with the different buttons 21 the damper will be arranged so as to control the fire for the weather indicated by the notations on the 105 plate 18. Nuts 23 are threaded on the stems 20 and engage shoulders 24 of recesses 25 on the back of the plate adjacent the slots. The shoulders prevent the nuts from turning in tightening and loosening the buttons 21. 110

Other locking means may be provided if desirable.

In using my improved gage the gage is set in a convenient position, such as on the furnace as indicated in Fig. 1, and the person installing the same arranges the chains to control the damper mechanism as indicated above. Upon the fireman or person who takes care of the furnace desiring to start a fire he places the ring 17 on button 22 and permits it to remain there until his fire is started. Then if the weather is mild he pulls the chain down engaging ring 17 with the button 21 of slot marked "Mild." If it happens that the weather is colder he either places the ring 17 on the button under the notation "Cold" or "Ex. cold," as the weather demands. When it is desired to bank the fire for the night or at other times when very little or no fire is required the operator pulls the chain down and engages the ring 17 on the lowermost button 21 in the slot under the notation "Bank." When the fire is banked and the operator desires to start up the fire he simply takes the ring off of the button under the word "Bank" and places it on button 22 until his fire has livened up sufficiently, then moves the ring 17 to one of the buttons under the notations "Mild," "Cold" or "Ex. cold," as the weather demands. It will be apparent therefore that no adjustment or guess work by the operator is necessary for controlling the fire. The only thing he need do is to select the button under the proper notation and engage ring 17 with this button to control his fire.

I claim:—

1. The combination with a furnace draft

control means having a control chain, of a 40 gage; and a plurality of spaced members adjustably mounted on the gage, each member being adapted to engage the chain, one at a time, and hold the draft means in a position of adjustment.

2. The combination with a furnace draft control means having a control chain, of a 45 gage; and a plurality of chain-engaging buttons adjustably mounted on the gage at different longitudinal points of the latter.

3. A furnace draft mechanism controlling gage comprising a plate having a plurality of longitudinal slots, and a draft chain-engaging button adjustably mounted in each 50 slot.

4. In a furnace draft control means, a controlling gage comprising a plate having a plurality of longitudinal slots with recesses along the slots providing a shoulder at each 55 side of each slot; a draft chain-engaging button at each slot on the front of the gage; and a nut in each recess with its sides substantially engaging said shoulders and threaded on one of said buttons locking the latter on said gage.

5. In a furnace draft control means a controlling gage comprising a plate having a plurality of longitudinal slots graduated in length; and a plurality of draft chain buttons adjustably disposed in said slots at 60 different recesses from the lower end of the plate, the button in the shortest slot being 65 nearest the lower end of the plate.

In testimony whereof I have signed my name to this specification on this 20th day of 75 November, A. D. 1919.

HERMAN GOLDBERG.
